UNITED STATES PATENT OFFICE.

EARL P. WEBSTER, OF NIAGARA FALLS, NEW YORK, ASSIGNOR TO THE SHREDDED WHEAT COMPANY, OF NIAGARA FALLS, NEW YORK, A CORPORATION OF NEW YORK.

CARTON-MARKING DEVICE.

Application filed April 2, 1927. Serial No. 180,354.

This invention relates to a method and apparatus for applying markings to cartons or other like receptacles for the purpose of furnishing identifying data, preferably 5 of a secret character which can be read only by authorized persons who are provided with a key.

In the packing of various products of commerce in cartons, it is frequently desirable that a mark be placed on each carton to identify the packer, or to give the date of packing or other information of that kind. This mark should be not easily interpreted, should be inconspicuous and apparently 15 meaningless, and it is preferable to have the mark applied without effort or attention on the part of the packer.

The present invention is accordingly directed to the provision of a method and 20 apparatus for the purpose described which is particularly useful in connection with the filling of cartons which have flaps which are closed after the cartons are filled, and the apparatus by which this method can be practiced is one which acts as a support for the 25 carton during the filling operation, the device applying a secret marking when the carton is placed in position to be filled.

According to the new method, spaced lines 30 are placed on each carton packed, and these lines are preferably applied to one of the carton flaps by a scoring operation. One of these lines serves as a reference line and the other line which is placed at varying 35 distances therefrom, serves to identify the packer, for example. If desired, such reference lines may be placed one on each of a pair of opposite flaps of the cartons with an identifying line or lines between them 40 and the marks may conveniently be placed on the flaps while the flaps are in open position during the filling of the carton. Thereafter, when the flaps are folded to close the 45 carton in the usual way, the markings are visible and the data supplied by the marks may be read by means of an interpreting scale.

In one convenient form, the apparatus for marking the cartons may be mounted on a 50 wall of a packing table, against which the cartons rest during the filling operation. The cartons with their opposite flaps open are placed against this wall by the packer and as the cartons are moved to that position, the flaps on the opposite sides of the

carton are acted on by marking devices which may take the form of scoring wheels. When the carton has been filled it is withdrawn from the device, the flaps folded and sealed in the usual manner. Thereafter the 60 packer who filled any particular carton may be readily identified by means of a key scale which has points of reference which may be placed to register with the reference lines on the cartons and identifying numbers placed between the reference lines and corresponding to the numbers of the packers. 65

For a better understanding of the invention, reference may be had to the accompanying drawings, in which,

Fig. 1 is a view in perspective of the apparatus showing a carton in position,

Fig. 2 is a plan view of a portion of a closed carton showing the lines applied by 70 the device,

Fig. 3 is a plan view of the device with a part broken away,

Fig. 4 is a sectional view on the line 4-4 of Fig. 3,

Fig. 5 is a plan view of a portion of the 80 carton showing the interpreting scale in position,

Fig. 6 is a plan view similar to Fig. 3, showing a modified form of the apparatus, 85

Fig. 7 is a sectional view on the line 7-7 of Fig. 6.

Referring now to the drawings, the device is illustrated in the form suitable for applying identifying markings to cartons made 90 of paste board or other suitable material, similar to that shown at 10, each carton having end flaps 11 of which one only is shown, and side flaps 12 which are adapted to be folded over the end flaps and sealed 95 when the carton is closed. These cartons are filled on a packing table 13 having an upstanding wall 14 along one edge. Mounted on this wall in spaced relation are plates 15, but one of which is shown, each plate 100 having a guide flange 16 along one vertical edge, and the two plates 15 being disposed a suitable distance apart so that the cartons may be placed in position between them and supported by the flanges 16 during the packing operation. Each plate 15 at its upper end carries a clamping plate 17 by which is held the pintle 18 of a marking device, generally designated 19. The plate 17 is provided with a wing nut 20 and 110

screw by which it may be forced firmly against the pintle to hold the latter in position.

Each marking device consists of a body member 21 having a cavity 22 formed in it, a pin 23 extending between the end walls of the cavity and carrying scoring wheels 24 and 25. These scoring wheels are freely rotatable on pin 23 and are placed in different positions along the pin with spacing sleeves 26 holding the wheels in adjusted position. The body portion 21 has an extending guide plate 27 projecting beyond one edge of the cavity 22 and also carries a bearing plate 28 extending partially over the top of the cavity, and with its lower surface lying close to the teeth of the scoring wheels. These plates are held in position by screws 29 as shown. The plates 27 and 28 provide a slot between them by which a carton flap may be directed to the scoring wheels.

When a carton 10 is to be filled, its outer flaps 12 are folded to open position and the carton then moved over the table 13 into position between the flanges 16 of the plates 15. In this movement the flaps 12 ride over the plates 27 and each flap passes between the scoring wheels and an upper plate 28. Lines of scoring are now made on the lower surfaces of each flap 12, these surfaces being the outer surfaces of the flap when the flaps are in closed position. When the carton has been packed, it is removed from its position in the supporting apparatus, the end flaps 11 are turned in and the outer flaps 12 are turned in over them, whereupon the lines of scoring are visible as shown in Fig. 2. The carton is now closed by means of a sealing strip 30 which is placed so as to cover the opposed edges of the two flaps 12.

The scoring lines which are clearly visible but are apparently without meaning serve as a means of providing identifying data. For example, these lines may be used to identify the packer who filled the carton. For any such purpose, the outer lines designated 31 serve as reference lines and the lines 32 which are placed between the reference lines have a variable position which depends on the identifying data to be provided. When the identification is to be made, an interpreting scale 33 is placed on the top of the carton, this scale having lines 34 which serve as reference lines and are used in conjunction with the lines 31. The scale illustrated has two sets of digits from 1 to 0, and when the scale is in position, each line 32 lies opposite a digit in one of these scales and the digits so indicated represent the number identifying the packer. If by any chance the flaps are folded so that the fixed lines 31 are not properly spaced so as to register with the reference marks 34 on the scale, then the

scale is used to identify each variable line 32 separately, the identification in each instance depending on the spacing of a variable line 32 from its corresponding fixed line 31.

In the carton illustrated in Fig. 6, the identifying marks 32 may be interpreted to read "35," one of the lines 32 corresponding to "3" in one scale and the other to "5" in the second scale. By varying the position of the scoring wheels which produce the lines 32, different combinations of digits may be secured and by the use of two wheels, different packers having numbers from 0 to 99 may be identified.

In the form of the apparatus shown in Figs. 7 and 8, the construction is in general similar to that shown in the preceding figures, except the upper fixed plate 28 is dispensed with and a plate 34 is employed which is hinged at 35 to a plate 36 secured by screws at 37 to the body member 21. On the hinge pin 35 is mounted a presser spring 38 bearing on top of the plate 34, this form of the apparatus permitting cartons of material of different thicknesses to be marked without necessitating a change in the presser plates 28.

It will be seen that the new method provides a convenient means for placing identifying marks on cartons, these marks being clearly visible but apparently meaningless. These marks convey no information to anyone who is not provided with the interpreting scale and the application of the marks does not injure the appearance of the carton. As the marks are applied automatically when the carton is placed in position to be filled, the packing operation is not interfered with and the application of these marks in no way reduces the speed of the packers.

The new apparatus is of simple construction, readily adjustable so as to provide for a wide range of identifying marks, and not likely to get out of order or to become worn in use. While the method and apparatus have been illustrated and described as useful in applying markings by which the carton packer may be identified, it is apparent that this method may be similarly employed for indicating the date on which the carton was filled, the quality of the goods placed in the carton, and various other data of that character.

I claim:

1. A method of marking a group of cartons for identification, which comprises placing a visible but apparently meaningless mark on a flap of each carton to serve as a point of reference, and simultaneously placing another similar mark on a flap at a distance from the first marking, the spacing of the marks being variable and dependent on the data to be provided thereby.

2. A method of marking a group of cartons having flaps for purposes of identification, which comprises placing a pair of visible but apparently meaningless marks one on each of a pair of flaps of each carton, these marks having a fixed spacing when the flaps are in their normal closed position and serving as lines of reference, and placing marks on each of the flaps to lie between the first pair of marks when the flaps are in closed position, the second pair of marks having different relative positions with reference to the fixed marks depending on the data to be provided thereby. 5
- 10 3. A method of marking a group of cartons having flaps for purposes of identification, which comprises placing a mark on each of a pair of opposite flaps of each carton while these flaps are in open position, the marks being so placed as to lie at a fixed distance apart when the flaps are in closed position, and serving as lines of reference, and placing a mark on one of the flaps while this flap is in open position, this mark lying spaced 20 from one of the reference marks a distance which depends on the data to be furnished by the marks. 25
4. A method of marking cartons having flaps during the filling of the cartons, which comprises folding a pair of opposite flaps of a carton to open position, and placing a pair of marks on one flap, these marks being visible when the flaps are in normal closed position, and the distance between the marks varying in accordance with the identifying data to be provided thereby. 30
5. Apparatus for applying identifying marks to cartons having flaps, which comprises a table, supporting means on the table with which the carton may be engaged, and means carried by the supporting means for receiving the flaps of the carton in their normal open position, and applying identifying marks to these flaps. 40
- 45 6. Apparatus for applying identifying marks to cartons having flaps, which comprises a table, a pair of supports mounted on the table and adapted to receive a carton between them, and means carried by the supports for receiving opposite flaps of the carton in their normal open position and applying identifying marks to these flaps. 50
- 55 7. Apparatus for applying identifying marks to cartons having flaps, which comprises the combination of a table, a support having a slot at its upper end adapted to receive a carton flap, and means carried by
- the support for engaging the flap received in the said slot and applying identifying marks thereto. 60
8. Apparatus for applying identifying marks to cartons having flaps, which comprises a table having an end wall, plates mounted on the end wall in spaced position and serving as guides for a carton, and means carried by each plate for receiving a carton flap and applying identifying lines of scoring thereto. 65
9. Apparatus for applying identifying marks to cartons having flaps, which comprises the combination of a filling table, a pair of plates mounted upright thereon and spaced apart to receive a carton between them, a guide plate secured to each upright plate and serving as a support for a carton flap, means carried by the guide plate for applying identifying marks to the said flap, and a bearing plate above the marking means for holding the flap in position to be marked. 70
- 80 10. Apparatus for applying identifying marks to cartons having flaps, which comprises the combination of a table, a pair of upright plates mounted thereon in spaced relation to receive a carton between them, a body member carried by each upright plate, a pin in the body, scoring wheels mounted on the pin, and means carried by the body for receiving a carton flap and directing this flap to a position in which it is scored by the said wheels. 85
- 90 11. Apparatus for applying identifying marks to cartons having flaps, which comprises the combination of a table, body members mounted thereon in spaced relation to receive a carton between them, marking devices adjustably carried in each body member, and means carried by the body member for receiving a carton flap and directing this flap into position to be marked by the said devices. 95
- 100 12. Apparatus for applying identifying marks to cartons having flaps, which comprises the combination of a table, a pair of body members mounted thereon and spaced apart to receive a carton between them, marking devices carried by each body member, a guide plate for directing a carton flap to the marking devices, and a resilient bearing plate serving to press the carton flaps into engagement with the said marking devices. 105
- 110 In testimony whereof I affix my signature.
EARL P. WEBSTER.
